Application July 30, 1948, Serial No. 41,580

21 Claims. (Cl. 242—155)

1

The present invention relates to devices for introducing tension into filamentary material, such as yarn, and comprises a novel device of this character which may be advantageously employed with untwisted filamentary material, hereinafter called "zero twist" yarn, as well as with yarn of low or of high twist. The new device is simple of construction, is quick to respond to variations in yarn tension and insures even distribution of tension in the filaments of the yarn strand.

Various tensioning devices have heretofore been suggested and used but none of the prior art devices has been entirely satisfactory, particularly when used to introduce tension into zero or low twist yarn. Among the known devices are those wherein the yarn is drawn between rotatable disks which are spring biased into engagement. Other known devices are those wherein the yarn is caused to travel over fixed curved surfaces, such as pins, which act as tension amplifiers. In both such types of devices the tension introduced into the yarn is due to the friction between the yarn and the surface over which it moves. These devices, because of the relative movement of the yarn with respect to a surface, tend to roughen the yarn and are unsatisfactory. They result in excessive damage to the outer filaments of the yarn with consequent retardation of broken ends of such filaments relative to the body of the yarn. Particularly in connection with twisting devices, where yarn must be under relatively high tension while traveling at a rapid rate, there has been a need for a positive acting tension device that does not have the disadvantages inherent in the prior art devices.

The primary object of the invention is, therefore, to provide a tension device suitable for use with yarn of any degree of twist, including zero twist.

Another object of the invention is to provide a yarn tension device which is readily adjustable over a relatively wide range of applied tension.

Still another object of the invention is to provide a device of the above described character in which there is an even distribution of tension in the filaments of the yarn strand.

A further object of the invention is to provide a tension device for yarn in which the tension introduced by the device is automatically varied in response to variations in input tension of the yarn and in a direction to maintain substantially constant tension.

Other objects of the invention will become apparent as the description proceeds.

Various tension devices embodying the inven-

2

tion are illustrated in the accompanying drawings of which:

Figs. 1 and 2 are side and front views, respectively, of a simple tension device embodying the invention and particularly suitable for use in quilling operations;

10 Figs. 3 and 4 are side and front views, respectively, of a yarn tension device of the general type of that of Figs. 1 and 2 but provided with means automatically responsive to a function of the outflow path of the yarn for varying the tension introduced by the device;

15 Figs. 5 and 6 are diagrams representing other constructions of tension devices of the type of Figs. 1 and 2;

Figs. 7 and 8 are diagrams representing other constructions of tension control devices of the general type of that of Figs. 3 and 4; and

20 Figs. 9 and 10 are side and top plan views, respectively, of a tension device representing still another embodiment of the invention.

In each of the illustrative embodiments of the invention hereinafter to be described, one of a pair of nip rollers is yieldingly urged against a 25 brake. The yarn or other filamentary material passes between the rollers and in the preferred embodiments of the invention contacts the surface of each through a substantial angle so as to prevent relative slippage between the yarn and either roller. The frictional resistance offered by the brake to rotation of the rollers by the 30 yarn introduces a corresponding tension into the yarn. In the preferred embodiments of the invention the yarn is so threaded through the device that the tangential pull of the yarn on one or the other of the rollers tends to decrease the pressure between the braking surface and the braked roller with increase in back tension of the 35 yarn. Thus a preferred tension device introduces a tension into the yarn which is maximum when the input yarn tension is a minimum and which decreases as the input tension increases. By adjustment of the spring or other biasing means, the tension added by each device 40 may be varied. Such adjustment may be effected manually, or, as hereinafter described in connection with the embodiments of the invention illustrated in Figs. 3, 7 and 8, such adjustment 45 may be made automatically in response to a function of the outflow path of the yarn.

In the specific tension device of Figs. 1 and 2, to which reference may now be had, the nip rollers are indicated at 2 and 4. The axle 6 of roller 2 is journaled in lugs 8 extending from a support frame 10. The axle 12 of roller 4 is journaled in the ends of a pair of arms 14, which are supported at their other ends by a pin 16. The

pin 16 is journaled in one end of a leaf spring 18, the other end of which is secured to the frame 10. The frame 10, adjacent the roller 4, has a re-entrant section 20 intermediate shoulders 22. The spring 18, through the arms 14, yieldingly urges the roller 4 into contact with the roller 2 and into contact with the shoulders 22 of the frame. Adjustable screw means 24, carried by the frame and engaging the spring 18 provides the means for adjustment of the pressure between the roller 4 and braking surfaces 22.

Inflow and outflow guides for the yarn may be mounted directly on the frame, as indicated at 26 and 28, or may form parts of any standard device with which the tension unit is associated. The yarn, indicated by A, after passage through the inflow guide 26, makes a half turn about the roller 4, on the side of the roller adjacent the frame 10, passes through the nips of the rollers and then contacts roller 2 through substantially 90° in transit to the outflow guide 28. The re-entrant section 20 provides clearance for the yarn in passing around the roller 4 so that there is no frictional engagement of the yarn with any fixed surface in its travel between the guides. The pivotal mounting of the arms 14 on the spring 18 permits the roller 4 to be swung away from the frame 10 for ready threading of the device. Both rollers 2 and 4 may be made of rubber, or rubber surfaced, but preferably roller 4 is of relatively hard, wear-resisting, material such as nylon or steel. The shoulders 22 of the frame, providing the braking surfaces for roller 4, may be formed of any material having a suitably high coefficient of friction with respect to the material of the roller.

It will be apparent from the above description that the tension device of Figs. 1 and 2 functions as hereinbefore described. The leaf spring 18 urges the rollers 2 and 4 into contact and also urges the roller 4 into contact with the braking surfaces 22. If the yarn A as it approaches roller 4 is under no appreciable back tension, the pressure between the roller 4 and the braking surfaces, and hence the frictional drag on the roller 4 will be constant when the rollers are rotated by the yarn. When there is back tension in the yarn, a component of force is created tending to lift the roller 4 from the braking surface. This reduces the frictional drag on the roller 4 with corresponding reduction in the tension introduced by the tension device. By adjustment of screw means 24, the pressure between the roller and braking surfaces due to the spring 18 may be varied over a relatively wide range. As the yarn in its travel between the guides 26 and 28 has no sliding contact with any surface, damage to the filaments thereof is avoided. The guides themselves need offer but slight frictional resistance to the yarn flow. They may be shaped to provide only a small angle of contact with the yarn and hence tension added thereby will be a minimum. The pressure between the rollers 2 and 4 insures even distribution of tension among the filaments of the yarn strand.

The tension device of Figs. 1 and 2 may be advantageously employed wherever tension is to be introduced into traveling filamentary material. For example, the device may be used in coning, quilling, spooling or other winding operation and also in twisting and doubling operations. It is particularly useful with yarn of low or zero twist and in operations where the yarn travels at relatively high speeds.

In the tension device of Figs. 1 and 2 auto-

matic compensation for input tension variations is provided, but manual adjustment only of the bias pressure between roller and brake is shown. Hence, for any specific adjustment of the bias pressure, the device tends to maintain constant output tension. By the construction illustrated in Figs. 3 and 4, to which reference may now be had, automatic adjustment of the bias pressure in response to a function of the angle of take-off of the yarn from the outflow guide is obtained. Such automatic adjustment of the bias pressure between the braked roller and the braking surface is of particular value when the yarn, upon emergence from the tension device, is free to balloon, as in twisting operation, as it provides automatic compensation for changes in balloon shape resulting from tension variations introduced by auxiliary take-up equipment.

In Figs. 3 and 4, the nip rollers 2a and 4a are indicated as of different diameter. Roller 2a, the larger of the two, is preferably of rubber, or is rubber surfaced, while roller 4a is preferably a hard surfaced roller. The axle 6a of roller 2a is journaled in bearings in arms 8a integral with the support frame 10a of the device. The frame 10a is provided with a pair of spaced braking surfaces 22a for engagement with the surface of roller 4a. A lever arm 30 is pivotally mounted at one end on the frame 10a and carries at its other end a yarn outflow guide 28a. The inflow guide comprises an eyelet 26a carried by the frame 10a. A small rod or pin 31 of sapphire or the like wear-resisting material is mounted in the eyelet 26a transversely of the inlet passage for passage of the yarn thereover. When the yarn is drawn off over the end of a supply package and passed directly to the tension device, the pin resolves the rotational motion of the yarn into reciprocatory motion and hence causes the yarn to transverse the roller 4a, spreading the wear thereof. The axle 12a of roller 4a is journaled in the ends of a pair of arms 14a of sheet spring material which are interconnected at their other ends by a cross member 32 which spans arm 30 near the outflow guide 28a and is pivotally mounted thereon by means of a pivot pin 34. A compression spring 18a, engaging a stud 36 carried on arm 30 and a fixed part 38 on the frame 10a, tends to rock the arm 30 about its pivot on the frame in a direction to urge the roller 4a against the surfaces 22a and against the roller 2a. Pressure between the rollers is also provided by the bowed spring arms 14a. The stud 36 is mounted on a screw 39 to permit of manual adjustment of the compression of the spring 18a and consequently of the bias pressure between the roller 4a and brake surfaces 22a.

In the particular embodiment of the invention illustrated in Figs. 3 and 4, the outflow guide 28a is rotatably mounted in the arm 30, as by ball bearings (not shown), and has a yarn passage 40 therein, the extended axis of which is substantially tangent to the surface of roller 2a. Passage 40 gradually increases in cross section in the direction of yarn travel. The surface of the guide at the outlet end of the passage is rounded and smooth, preferably polished, for minimizing friction between the yarn and guide when the yarn is drawn off at an angle to the axis of the passage.

The path of the yarn A through the device of Figs. 3 and 4 is the same as through the device of Figs. 1 and 2, namely, from the inflow guide 26a, around and in contact with the roller 4a

75 on the side thereof adjacent the braking sur-

faces, around and in contact with roller 2a through an arc of substantially 90° and then to the passage 40 of the outflow guide 28a. The direction of the path of the yarn beyond the outflow guide and, therefore, the length of contact of the yarn with the rounded surface of the guide depends, of course, upon the location, relative to that of the tension device, of the particular yarn takeup mechanism with which the tension device is associated. Such take-up mechanism may include a moving element, such, for example, as used for traverse of a yarn package, or the moving element may be a rotating flyer interposed in the yarn path between the tension device and take-up mechanism. No take-up mechanism is indicated in the drawing as such mechanisms are well known, and so far as the functioning of the device of Figs. 3 and 4 is concerned, it is immaterial what type of mechanism is assumed as the cause of travel of the yarn through the tension device. If the direction of flow of the yarn from the outflow guide to the take-up mechanism is at a substantial angle to the axis of the passage 40, for example if the outflow direction makes an angle α with the axis of passage 40, as indicated in Fig. 3, there will be a component of force acting through the guide on arm 30 in a direction tending to counteract the compression in the spring, and, therefore, tending to reduce the pressure between the roller 4a and braking surfaces 22a. If the angle α of take-off of the yarn with respect to the axis of the passage 40 decreases so that the yarn contacts the surface of the guide 28a through a smaller angle, the component of force opposing the action of spring 18a decreases. Conversely, with a change of take-off angle that increases the angle of contact of yarn with the guide surface, the component of force opposing the action of spring 18a increases. Thus the maximum tension introduced by the device is automatically decreased as the angle of contact of the yarn with the outflow guide increases. This feature of the device of Figs. 3 and 4 provides compensation, at least in part, for the fact that tension introduced by the friction between the yarn and the surface of the outflow guide increases exponentially with the angle of contact of the yarn with the surface.

The relation between the magnitude of the component of force tending to decrease the pressure between roller and braking surfaces and the angle of take-off of the yarn is

$$P_y = T_1 (1 - e^{f_g \alpha} \cos \alpha) \quad (I)$$

where P_y is the component of resultant force acting downwardly on the guide, T_1 is the tension in the yarn at entrance to the passage 40, f_g is the coefficient of friction between the material of the guide and the yarn and α is the angular change of direction of the yarn at the guide. When f_g is of the order of 0.2, the rate of change of P_y with α reaches a maximum when α is approximately 113°. Thus when the yarn is drawn from the guide 28a at approximately that angle, maximum sensitivity of the tension device to change of direction of outflow of the yarn is obtained.

To derive Formula I it is only necessary to find the component parallel to the axis of passage 40 of the resultant of the tensions in the yarn, before and after leaving the guide. As the tension beyond the guide, T_2 , is equal to

$$T_1 e^{f_g \alpha}$$

expressions for the resultant force and for the desired component are readily obtained. It will be understood that the control level, that is, the bias pressure F_s , for any particular setting of the biasing means, will be equal to $K P_y$ where K is a constant determined by the configuration or geometry of the parts of the device.

Two embodiments of the invention have now been described, one in which the tension introduced by the device is varied in response to back tension in the yarn, and the other in which there is an additional response to angle of take-off of the yarn. In each device the resilient means biasing a roller against a braking surface has been shown as an adjustable spring. In Fig. 5 is diagrammatically illustrated a tension device embodying the invention in which magnetic means instead of spring means is employed to provide the bias necessary for braking.

20 In Fig. 5, 42 represents a horse shoe type magnet having hook-shaped pole face extensions 44, of which only one appears in the view shown in the drawing. The braked roller 4b is formed of rubber or the like and is mounted on an iron shaft 12b which serves as the armature of the magnet. A frame 10b of brass, aluminum or other non-magnetic material supports the roller 2b and the outflow guide 28b and has braking surfaces 22b engaged by the roller 4b. The attraction of the pole face extensions 44 for the shaft 12b causes the roller 4b to be pressed against the braking surfaces 22b and against the roller 2b. As the attraction of a magnet for its armature is a force acting, when the armature is withdrawn, to return the armature to attracted position, it is, in that respect a "resilient" force and hence in the device of Fig. 5, the roller 4b may be said to be resiliently biased against the braking surface and against roller 2b. Suitable inflow guide means 30 may be mounted within the arms of the magnet 42, as indicated in dotted lines at 26b. As in the tension devices of Figs. 1 and 3, the yarn A passes from the guide 26b, around, and in contact with, the roller 4b on the side engaging the braking surfaces 22b, then between the rollers, around, and in engagement with, the roller 2b for a quarter turn and finally to the outflow guide 28b.

50 The pole face extensions 44 are preferably mounted for adjustment toward and away from the shaft 12b so as to permit of adjustment, as by the slot and screw indicated at 24b, of the maximum pressure between roller 4b and the braking surfaces 22b. The operation of the device of Fig. 5, being the same in all respects as that of Figs. 1 and 2, needs no further description. The free mounting of the roller 4b of Fig. 5 eliminates the necessity of providing bearings for its shaft and likewise simplifies the threading of the device as will be readily apparent.

55 In the tension devices so far described, the mechanical advantage (ratio) between the yarn and braking forces is unity. The slope of the curve representing the relation between the tension, T_0 , at input to the rollers and the tension T_1 at output therefrom, for any given bias pressure, F_s , between the braking surface and the braked roller, depends only upon the coefficient of friction f_b between the materials of the roller and of the braking surface. Expressed mathematically this relation is

$$\frac{dT_1}{dT_0} = \frac{(1 - f_b)}{(1 + f_b)} \quad (II)$$

75 Thus, theoretically, complete compensation for variations in input tension with the devices so

far described is obtained only when f_b is equal to one. Actually, from a practical standpoint, reasonable operation of the devices and satisfactory compensation for input tension variations is obtained with values of f_b of from about 0.3 to about 0.4.

Fig. 6 illustrates a tension device wherein the mechanical advantage between the yarn and braking forces is greater than unity. This increase in the ratio between the forces is the mechanical equivalent of an increase in the term f_b of Equation II and hence, for a given value of f_b , the slope of the characteristic curve of the device of Fig. 6 will be less than that of devices having a one-to-one ratio. In the particular device of Fig. 6 there is approximately a two-to-one ratio between the yarn and braking forces and hence the coefficient of friction between the braking surface and braked roll is effectively doubled.

In the device shown in Fig. 6, the nip rollers, indicated at 2c and 4c, are of equal diameter. Roller 2c, which is preferably the hard surfaced roller, is the braked roller. It is rotatably mounted in lugs 8c which extend downwardly from an upper side of an open framework 10c. Roller 4c, which is preferably of rubber, is carried on the end of an arcuate arm 14c which also carries brake shoes 22c for engagement with the roller 2c. The arm 14c is pivotally mounted at 45 on an arm 46 which, in turn, is pivotally suspended from an upper side of the frame 10c. A tension spring 18c is secured at one end to arm 46 and at its other end to a nut 48 threaded on a screw 24c. The screw 24c is carried by the frame and provides the means for adjustment of the tension of spring 18c. The frame 10c is provided with substantially aligned inflow and outflow guide passages indicated at 26c and 28c respectively, and a traversing pin 31 is provided in the inlet guide passage, as described in connection with the device of Figs. 3 and 4. In the particular construction of device illustrated in Fig. 6, the axes of the nip rollers are in substantially the same horizontal plane whereas the pivotal axis 45 of the arcuate arm 14c on arm 46 is above this plane. Hence, under the tension of spring 18c, the force acting at the axis of roller 4c has a vertical component, which, in the absence of the brake shoe, would cause the roller 4c to ride up on the roller 2c. This vertical component thus provides the bias pressure between brake shoe and roller 2c whereas the horizontal component provides the pressure between the rollers.

The yarn path through the device is from the inlet guide 26c, around and in contact with the roller 4c, between the nips of the rollers and then around, and in contact with, the roller 2c and on the side engaged by the brake shoes 22c and thence to the outlet guide 28c, the yarn, in this embodiment engaging the surface of each roller through substantially 180°. Back tension in the yarn acts downwardly on roller 4c and hence tends to reduce the braking pressure on the roll 2c. The mechanical advantage between the yarn and braking forces is the ratio of the respective radii from the pivot 45 to the axis of roller 4c and to the point of braking; calling this ratio R, the slope of the characteristic curve of the device is

$$\frac{dT_2}{dT_1} = \frac{(1 - Rf_b)}{(1 + Rf_b)} \quad (III)$$

which, when R equals 2, reduces to zero for $f_b = 0.5$.

Thus, the construction of Fig. 6, as compared to that of Fig. 1, for example, will result in more nearly complete compensation for changes of input tension when using similar friction surfaces or, for equal compensation, permits the use of materials of lower coefficient of friction.

In the construction of Fig. 6 there is substantially 180° wrap of the yarn about each of the rollers. This is advantageous as it insures non-slipping contact of the yarn with the rollers and permits the force transmitting roller, in this instance, the roller 2c, to be of hard wear-resisting material.

Another construction of a device of the general type of that of Figs. 3 and 4 is diagrammatically indicated in Fig. 7, to which reference may now be had. In this embodiment of the invention, the axle 12d of the braked roller 4d is mounted in arms 14d which are pivotally mounted on the base or frame 10d while the cooperating nip roller 2d is rotatably carried by a movable member 52 which also carries the output guide 28d. Member 52 is pivotally mounted on the frame 10d, as indicated at 54, and is biased by a compression spring 18d in a direction to apply pressure between the rollers and between roller 4d and braking surfaces 22d on a block 56 secured to the base 10d. The yarn A, upon leaving the inlet guide, which may comprise a passage 26d in the frame 10d, passes around, and in contact with, the roller 2d, then between the nips of the rollers, around and in contact with the roller 4d on the side thereof in engagement with the braking surfaces and to the outlet guide 28d. As the outlet guide 28d is carried by the biased element 52, the device will be sensitive to the angle of outflow of the yarn as is the device of Figs. 3 and 4. Manual adjustment of the maximum pressure between roller 4d and the braking surfaces 22d can be effected by adjustment of the compression of spring 18d as in the embodiments of the invention heretofore described.

In Fig. 8 as illustrated another embodiment of the invention wherein there is automatic adjustment of the device in response to a function of the outflow path. The device includes an E-shaped frame 10e, the lower leg of which may include the inlet guide 26e, the middle leg of which provides the braking surfaces for the roller 4e and the upper frame of which rotatably supports parts now to be described. A tubular member 58, which is rotatably mounted in ball bearings 60 in the upper leg of the frame 10e, has a disk 62 secured thereto above the frame, and a cam 64 secured thereto below the frame. A generally conical member 66 is secured to the upper end of member 58, or is formed integral therewith. Pivotedly supported on the middle leg of the frame 10e is a curved arm 68 which carries at its free end a follower 70 for the cam 64. Arm 68 has a leaf spring 71 secured thereto which is engaged by a screw 72 threaded through the frame 10e. The action of spring 71 provides sufficient pressure between follower 70 and cam 64 to insure continued contact therebetween and to provide frictional resistance to rotation of the cam and the parts associated therewith. A second leaf spring 74 secured to arm 68 provides resilient mounting for the braked roller 4e, the axle of the roller being journaled in arms 14e which are secured at their other ends to the spring 74. The axle of the cooperating roller

2e is journaled in arms 76 pivotally mounted on the frame near the base of the upper leg and held in engagement with a fixed stop 77 by means of a spring 79.

With the above described arrangement, the yarn A passes from the inlet guide 26e, contacts the surface of roller 2e through an arc of more than 180°, passes between the rollers, then around and in contact with roller 4e on the side adjacent the braking surfaces on the middle leg of the frame and then up through the tubular member 58. When the yarn is drawn off from the device in a downwardly direction, as indicated, to an element so moving as to cause the yarn to balloon about the tension device, it will engage the edge of disk 62. If the balloon tends to contract, due to increase in tension of the yarn, the friction between the yarn and disk will tend to rotate the disk in the direction of rotation of the balloon and in opposition to the frictional resistance to rotation offered by the pressure exerted on the cam by its follower. When the output tension in the yarn is sufficient to move the disk and cam about the axis of member 58, the cam, acting through the follower, rocks the arm 68 about its pivot on the frame in a direction to reduce the pressure between the roller 4e and the braking surfaces. This reduces the tension introduced by the device and consequently also the output tension in the yarn. As in the other embodiments of the invention, increase in input tension in the yarn also tends to reduce the braking pressure. The screw 72 provides means for manually adjusting the maximum pressure between braking surfaces and roller 4e. The device of Fig. 8 may be readily threaded by swinging roller 2e into the position illustrated in dotted lines on the drawing. It will be understood that the end of the middle leg of the frame 10e will be cut away beneath the central part of roller 4e to provide clearance for the yarn in its passage around that roller.

A tension device particularly adapted for use with an incremental twister is illustrated in Figs. 9 and 10. In this embodiment of the invention the axes of the nip rollers 2f and 4f are journaled in a pair of spaced arms 78 which are interconnected and pivotally mounted on the frame or platform 10f by means of a pin 80. The arms 78 are preferably of sheet spring material and intermediate the bearings for the axles of the rollers 2f and 4f have U-shaped loops 82 therein providing compression spring action urging the rollers into engagement. The section interconnecting the arm 78 above the frame 10f is provided with an upstanding flange 84 to which is secured one end of a compression spring 18f. The other end of spring 18f engages a shoulder 86 on a shaft 88 which is screw threadedly mounted in a vertical support 90 and locked thereto by a nut 92. A knurled head 93 on the end of the shaft serves for adjustment of the pressure exerted by the compression spring 18f on the flange 84. Support 90, which is secured, as by screws 94, to any suitable fixed part of the particular yarn handling mechanism with which the device is to be associated, is preferably formed integral with the frame 10f.

An inlet passage 26f in the platform 10f beneath the rollers serves as a guide for the yarn, A and the yarn travels upwardly through the passage 26f and between the rollers 2f and 4f.

At least one, and preferably both, rollers 6 and 8 are made of rubber or are rubber coated so

that the yarn will be gripped firmly but will not be bruised.

Roller 4f normally engages the platform 10f, as shown in Fig. 9 and is pressed against the platform by the compression of the spring 18f tending to rotate the arms 78 about the pin 80 in a counterclockwise direction.

In the operation of the device of Figs. 9 and 10, the rollers which grip the yarn firmly therebetween under the action of the spring metal loops 82, are rotated by the yarn as it is drawn up through the device, roller 4f offering resistance to rotation due to the friction between that roller and the platform 10f. Increase in yarn tension tends to rock the arms 78 against the biasing action of spring 18f and thus reduces the frictional resistance to rotation of the roller 4f. Spring 18f is adjusted so that, when the tension in the yarn is that desired, roller 4f has but slight frictional engagement with platform 10f. Adjustment of the compression of spring 18f is readily effected by rotation of knurled head 93 of shaft 88.

The invention has now been described with reference to seven different embodiments thereof in each of which tension is introduced into travelling filamentary material or yarn by frictional drag opposing rotation by the yarn of one of a pair of nip rollers. In each of the preferred embodiments of the invention increase in back tension of the yarn reduces the pressure between the braked roller and the braking surface providing the frictional drag on the roller. In each embodiment of the invention resilient adjustable means are provided for biasing the braked roller into engagement with the braking surface and in certain of the embodiments of the invention automatic adjustment of the bias pressure in response to a function of the outflow yarn path is provided. In each case the yarn is gripped firmly at the nips of the rollers and tension introduced by the frictional drag involves no sliding contact of the yarn with a fixed surface and hence relatively high tension may be introduced into fine yarns of low or zero twist without damage thereto. As heretofore indicated, the nip rollers may be of the same or of different diameter, both may be of relatively elastic material or one may be hard surfaced.

50 The following is claimed:

1. A tension device for traveling filamentary material which comprises a member having a frictional surface, a first rotatable element having a cylindrical surface in engagement with said frictional surface and reciprocally movable relative thereto to change the frictional drag on said element, a second rotatable element having a cylindrical surface in frictional engagement with the cylindrical surface of said first element, whereby both elements are adapted to be rotated by passage of filamentary material therebetween and whereby when the direction of travel of material during such passage is away from said frictional surface such passage can apply a force upon said first element to tend to remove it from engagement with said frictional surface, and resilient means urging said first element into engagement with said frictional surface.

2. The tension device according to claim 1 including inflow and outflow guide means for the material positioned with respect to said rotatable elements to provide a generally S-shaped path for the material in passing between said rotatable elements thereby insuring driving engagement

11

of the material with each rotatable element over a substantial angle.

3. The tension device according to claim 1 including an output guide for the material and means cooperating therewith, tending to vary the pressure between said frictional surface and said first element in accordance with the relation

$$P_y = T_1 (1 - e^{f_b \alpha} \cos \alpha)$$

where P_y is the component of force acting on the 10 guide in a direction to decrease the pressure between said frictional surface and first element, T_1 is the tension in the material at entrance to 15 said guide, f_b is the coefficient of friction between the material and the guide and α is the angular change in direction of the material at said guide.

4. A tension device for traveling filamentary material comprising in combination, a pair of nip rollers adapted to be rotated by travel of filamentary material therebetween, a member having a surface positioned in engagement with the cylindrical surface of one of said rollers to apply a frictional drag thereto, support means for said rollers providing pivotal movement therebetween including resilient means for biasing said last mentioned roller and said member surface into frictional engagement, and guide means for the material positioned relative to said rollers and to said member surface to lead material to the nips of said rollers in a direction away from said surface whereby tension in the material acts in opposition to said resilient means to reduce the pressure between said last mentioned roller and member surface.

5. The tension device according to claim 4 wherein said support means for said rollers comprises a part fixed with respect to said member surface and rotatably supporting one of said rollers, and an arm linked to said part and relatively movable with respect thereto, said arm supporting the other of said rollers and said biasing means operating through said arm to urge said last mentioned roller into engagement with said member surface.

6. The tension device according to claim 4 wherein said guide means are positioned with respect to said rotatable elements to provide a circuitous path for the material in passing between said rotatable elements thereby insuring driving engagement of the material with each roller over a substantial angle.

7. The tension device according to claim 4 wherein said support means for said rollers comprises a fixed part supporting one of said rollers and a movable part supporting said member and the other roller, said biasing means operating through said movable part to urge said member surface into engagement with the roller supported on the fixed part and to urge said rollers into engagement.

8. The tension device according to claim 4 including means for adjusting said biasing means to vary the maximum pressure between said member surface and said roller.

9. The tension device according to claim 4 wherein said guide means includes an outflow guide and wherein there is provided means associated with said outflow guide and responsive to a function of the angle of outflow of the material therefrom for automatically adjusting said biasing means.

10. The tension device according to claim 4 including means associated with said guide means resolving any rotational motion of the material at inflow to the device into reciproca-

12

tory motion substantially parallel to the axes of the rollers whereby, when material is delivered to the device with rotational motion, the material will traverse the rollers with limited back and forth motion axially thereof during passage through the device.

11. A tension device for traveling filamentary material which comprises a member having a frictional surface, a first rotatable element in engagement with said surface, a second rotatable element in frictional engagement with said first element whereby both are adapted to be rotated by passage of filamentary material therebetween, pivotally connected support means for said elements and said member permitting relative movement between the surface and said first element, resilient means biasing said first element and surface into engagement, and guide means for the material positioned to insure a substantial angle of contact of the material with each element whereby the longitudinal pull of the material on one element acts in opposition to said resilient means to reduce the pressure between said surface and said first element, the rate of change of the output tension T_1 in the material with change of input tension T_0 being substantially equal to

$$(1 - R f_b) / (1 + R f_b)$$

30 where f_b is the coefficient of friction between the surface and said first element and R is the ratio of the respective distances to the pivotal point of connection of the support means of the point of application of the tangential pull of the material on one element and of the point of application of the frictional drag of said surface on the first element.

12. The tension device according to claim 11 wherein the tangential pull of the material acts on the first element whereby R is substantially equal to unity.

13. The tension device according to claim 11 wherein the tangential pull of the material acts on said second element and wherein said second element is carried on said support means at a distance from the pivotal point of connection of the support means greater than that of the point of application of the frictional drag of said surface on the first element from the pivotal point whereby R is greater than unity.

14. A tension device for traveling filamentary material comprising a pair of nip rollers adapted to be rotated by passage of filamentary material therebetween, inflow and outflow guide means for the material so positioned relative to said rollers as to insure contact of the material with each roller over an arc of substantially 90°, a brake member positioned for frictional engagement with one of said rollers, support means for said rollers and said brake member including two relatively movable parts of which one is fixed relatively to said inflow guide means, one of said parts supporting said brake member and one of said rollers and the other of said parts supporting the other roller, and resilient means interconnecting said parts and biasing the brake member carried by one part into engagement with the roller carried by the other part, the tangential pull of the material on one of said rollers tending to reduce the braking pressure, whereby the device tends to compensate for variations in back tension of the material.

15. The tension device according to claim 14 wherein the brake member is carried by the movable part of said support and such part includes

a link pivotally mounted at one end on the fixed part of the support means and an arm pivotally connected to said link, the roller being carried by said arm at a greater distance from the pivotal point of connection with said link than is the brake member whereby back tension in the material acting on the roller not in engagement with the brake member tends to move said brake member out of contact with the other roller.

16. A tension device comprising in combination 10 a pair of spaced guides, a pair of nip rollers positioned between said guides, a structure having a surface positioned for engagement with one of said rollers, means biasing said last mentioned roller against said surface, and means supporting 15 said one roller for relative movement with respect to said structure and to provide passage of filamentary material in transit between said guides and between said nip rollers with a substantial angle of contact with said biased roller on the 20 side facing said surface so that tension in the material tends to reduce the pressure between said biased roller and said surface.

17. A tension device for traveling filamentary material comprising in combination, a pair of 25 nip rollers adapted to be rotated by filamentary material traveling therebetween, support means for said rollers comprising two parts pivotally coupled together, one of said parts having a braking surface positioned for engagement with one of said rollers, said last mentioned roller being carried by the other of said parts, and resilient means associated with said support means for biasing said last mentioned roller into engagement with said surface, whereby when 30 filamentary material travels between said rollers and contacts the surface of the biased roller over a substantial arc on the side thereof adjacent said braking surface, tension in the material tends to move said roller away from said surface, and outflow guide means operatively coupled with said resilient means to vary the biasing pressure between said last mentioned roller and said surface in response to a function of the tension in the material beyond said outflow 35 guide means.

18. A tension device comprising a frame, brake surfaces on said frame, a first roller having an axle journaled in said frame, a spring strip secured at an end to said frame, a member pivotally coupled to the other end of said strip and a second roller rotatably supported by said member with its surface in engagement with said brake surface and with said first roller, said spring acting through said support members to apply 55 pressure between the rollers and between said second roller and the brake surfaces on said frames.

19. A tension device for filamentary material comprising in combination a frame, additive tension means carried thereby, said frame having a 60 passage therein of generally circular cross-sec-

tion for leading filamentary material to said means, and a rod engageable by material and extending transversely of said passage for resolving any rotation motion of material at inflow to the device into reciprocatory motion axially of said rod to impart limited traversing movement to said material as it passes through said means.

20. A tension device for traveling filamentary material which comprises a member having a frictional surface, a first filament guide roller having a cylindrical frictional surface adapted to engage the first named frictional surface, means to mount the member and first roller to permit relative movement of the frictional surfaces toward and away from each other, means to urge the frictional surfaces into engagement yieldingly, a second filament guide roller, means to mount the second guide roller with its filament guide surface in rolling contact with the filament guide surface of the first roller inflow guide means on one side of said filament guide rollers, and output guide means on the opposite side of said filament guide rollers, said rollers being arranged with respect to said member so that when filamentary material travels between said rollers and contacts the frictional surface of said first roller over a substantial arc on the side thereof adjacent the frictional surface of said member, tension in the material tends to move said first roller away from said member surface.

21. A tension device for traveling filamentary material comprising a support, input and output guides disposed in spaced relation on said support and through which said material is adapted to be drawn, a pair of rollers positioned between said guides on said support and yieldingly supported for relative movement both radially and circumferentially of each other, said material in traveling through said device being passed between said rollers and wrapped therearound in opposite directions over a substantial arc of at least one of said rollers, a brake member positioned for engagement with said one of said rollers, and means biasing said rollers into engagement with each other and said one of said rollers into engagement with said brake member, the tension in said material acting to oppose said biasing means to cause said one of said rollers to be urged circumferentially of said other roller and in a direction away from said brake member.
